UNITED STATES PATENT OFFICE.

JOHN ECHOLS CRAMER, OF CARROLLTON, GEORGIA.

AQUATIC SIGNBOARD.

Application filed December 17, 1925. Serial No. 76,084.

This invention relates to signs and particularly to the display of signs on the surface of the water and has for its object the display of a sign above the surface of water, 5 preferably running water.

Another object of the invention is to anchor the sign in the water in such a way that it makes the best display and looks most attractive when viewed by persons in front of 10 the sign.

With these and other objects in view the nature of which will be disclosed as the description proceeds; I will now describe my invention in connection with the accompanying 15 drawings in which:

Figure 1 is a perspective view of one form of the sign; and,

Fig. 2 is a view of a modification.

A is the sign board which may be of one 20 wide board or of several separate boards joined together in any convenient way. Fastened to the lower end of the sign A is a float B preferably extending from one side to the other of the sign A and this float 25 must have sufficient buoyancy when resting on the water to support the sign board A sufficiently high above the water so that no part of the inscriptions or pictures on the sign board will pass below the water.

C is an anchor preferably of concrete, 30 though it may be iron, or a box of sand or rock varying in size according to needs, and arranged up-stream or down-stream relative to the sign board A, if the sign is in running water. In the anchor C, I place fasteners D which may conveniently be in the 35 form of staples attached to the anchor C as clearly shown in Figure 1.

E is a wire or rod attached at its outer 40 ends b to the sign board and at its middle portion to staples or fasteners D. This rod may be flexible, but I preferably make it rigid to hold the top of the sign board A in an upright position as clearly indicated in

Fig. 1. As shown in Fig. 1 of the drawings 45 the wire E forms three sides of a quadrilateral while the sign A forms the fourth side. Obviously the staples D hingedly holding one side of the quadrilateral will tend to 50 hold the sign from sidewise movement but allow up and down movement of the sign caused by the waves or swells of the water.

The anchor C may extend into the earth at 55 the bottom of the stream so as to prevent it from turning in any way and thus allowing

the sign board to become displaced, and I preferably connect the bottom of the sign board to the anchor C by rigid rods F.

This arrangement of the sign board with 60 stiff rods E and F holding respectively the top and bottom of the sign board causes a peculiar and pleasing up and down motion of the sign board as waves or swells in the water change the position of the sign board, especially if the water is running water, and 65 produces a pleasing effect when viewed from in front of the sign board. It may be advantageous in some cases to add sufficient weight to the bottom of the sign board to normally maintain it in its upright position. 70

The sign board, as a whole, including the attached float B, is inexpensive to produce, but when suitably located, for example, near a roadside or bridge, or in any body of water near any avenue of travel, it produces a most 75 pleasing and attractive advertising sign.

In Figure 2, I have shown a modification in which the float B' is on the other side of the sign board from what is shown in Fig. 1. In this modification the float and sign 80 board should be so proportioned that the top of the float will be practically on a level with the surface of the water. The rod E' attached to the sign board at b' and the chain F' and anchor C are similar in construction 85 and operation to the corresponding parts of Fig. 1.

The rods E or E' when the sign is properly located will be practically invisible and of course the anchors C and chain F' being 90 below the surface of the water will also be invisible as will most of the float B or B' and as the sign is raised and lowered by waves or swells or the running of the water, the peculiar motion given to it by the stiff rod 95 attached to the upper part and the rigid rod or flexible chain attached to the lower part, produces a peculiar and attractive motion to the sign.

What I claim as my invention is:

1. A sign board adapted to receive inscriptions or pictures on its surface, a float attached to the sign board at its lower portion to maintain part of the sign board sufficiently high above the supporting water to 105 render the inscriptions or pictures visible, an anchor and a rod hingedly connecting the top of the sign board with the anchor, the hinged portion extending horizontally across the top of the anchor so as to hold the sign 110

- board to a vertical movement, and a second connection between the bottom of the sign board and the anchor all arranged to maintain the sign board in upright position.
5. 2. An aquatic sign board adapted to display a sign above the surface of water comprising an upright sign board with a float to support part of it above the surface of the water, an anchor below the surface of the water and a one-piece rod with its middle portion extending horizontally across the top

of the anchor and horizontally attached to the anchor and its end portions attached to the upper part of the sign board, and a flexible connection below the water and between the anchor and the bottom of the sign board whereby the sign board is held to a vertical movement and restrained from sidewise movement. ¹⁵

In testimony whereof I affix my signature.

JOHN ECHOLS CRAMER.
